GIRDLE WITH AUXILIARY ABDOMINAL SUPPORT

Estelle Popp, New York, N.Y., assignor to Benjamin & Johnnes, Incorporated, Newark, N.J., a corporation of New Jersey

Filed Mar. 13, 1963, Ser. No. 264,903
2 Claims. (Cl. 128—547)

This invention relates in general to body-encircling garments and more particularly to a so-called "boneless, pull-on girdle" of either the waistline, high-top or panty type, or to an all-in-one corselet.

A primary object of the invention is to provide a body-encircling garment and particularly a girdle which includes a main portion endless or continuous circumferentially and has at least portions thereof elastically expandible and contractible so that the girdle can be pulled onto the body with the elastic portions yielding or stretching until the garment has reached the desired point on the body whereupon the elastic portions will hold the garment in the desired position and with the desired yielding support of the body, and auxiliary means connected to said main portion for drawing or tightening the garment around the body, particularly in the front zone or abdominal portion so as to provide an additional or auxiliary support for the abdominal wall.

Another object of the invention is to provide such a girdle wherein the auxiliary abdominal supporting means shall include a novel and improved construction and combination of a plurality of sections connected to the main portion of the girdle and separably connected together by a slide fastener, whereby after the girdle has been pulled onto the body, the abdominal supporting means can be placed under tension by closing of the slide fastener and thereby provide auxiliary support for the abdominal wall.

Other objects, advantages and results of the invention will be brought out by the following description in conjunction with the accompanying drawings in which

FIGURE 1 is a front perspective view of a girdle embodying the invention, showing schematically the garment in use position on the body with the slide fastener closed and the abdominal support drawn tightly against the abdominal wall;

FIGURE 2 is a similar view with the slide fastener in open position and with the abdominal support released;

FIGURE 3 is an enlarged front elevation of the girdle in flattened condition with the auxiliary abdominal support in the same condition as shown in FIGURE 1;

FIGURE 4 is a similar view showing the abdominal supporting means in the same condition as shown in FIGURE 2;

FIGURE 5 is a top plan view of the girdle from the plane of the line 5—5 of FIGURE 3;

FIGURE 6 is a similar view from the plane of the line 6—6 of FIGURE 4;

FIGURE 7 is an enlarged fragmentary horizontal sectional view on the plane of the line 7—7 of FIGURE 3;

FIGURE 8 is a similar view on the plane of the line 8—8 of FIGURE 4; and

FIGURE 9 is a fragmentary horizontal sectional view of the front portion of the garment taken on the plane of the line 9—9 of FIGURE 3.

While the invention may be embodied in different articles and different types of body-encircling garments, the invention has been shown in a generally known type of so-called "boneless, pull-on girdle" which includes a front panel A and a rear panel B and two side panels C that are stitched together to provide a circumferentially endless or continuous main portion.

2

The rear panel comprises a central section 1 formed of material that is elastic only longitudinally of the garment, that is, from the top edge to the bottom edge, but is non-elastic laterally or circumferentially of the garment; and two flank sections 3 each of which is elastic both longitudinally and circumferentially of the garment, the central section and the flank section being stitched together by longitudinal lines of stitches 4.

The side panels C are elastic longitudinally of the garment but non-elastic circumferentially of the garment and are secured to the flank sections 3 of the rear panel by lines of stitches 5. The side panels C are connected to the front panel A by lines of stitches 6, and the front panel comprises two sections 7 and 8 that are formed of fabric that is elastic both longitudinally and circumferentially of the garment; and the two sections are secured together by a seam 9 of known construction. As usual, the lines of stitches 4, 5 and 6 are such as to permit the stretching of the fabric sections which are connected by the stitches, but preferably the seam 9 is non-stretchable both circumferentially and longitudinally of the garment, the seam as shown comprising the overlapped edges of the two sections 7 and 8 that are overlaid by a tape 10 which is secured to the edge portions of both of the sections 7 and 8 by longitudinal lines of stitches 11.

It will be observed that the main portion of the girdle constructed as described can be pulled onto the body, the elastic sections providing sufficient expansibility or stretchability of the garment and also drawing the garment into tight fitting engagement with the body from a point below the hips to the waistline or above, the inherent elasticity of the main portion of the garment also providing a certain amount of support for the abdominal wall.

The present invention contemplates an auxiliary abdominal support which is constructed in such a way as not to interfere with the easy application of the garment to the body but which will provide additional tension and support in the zone of the abdominal wall and which can be brought into abdominal-supporting action or position by a simple "zip" or sliding of the slider of a slide fastener.

As shown, this auxiliary abdominal support D comprises two sections 12 and 13 one edge of each of which extending longitudinally of the girdle is secured by a line 45 of stitches 14 to one of the sections 7 or 8 of the front panel. The other longitudinal edges of the sections 12 and 13 are normally unconnected from the top edge of the garment to a point intermediate the upper and lower edges of the garment, preferably adjacent the lower edge 50 of the garment so as to normally provide an approximately V-shaped gap between those edges as shown in FIGURES 2 and 4.

In accordance with the invention, said edges are connectible and disconnectible by a quick acting fastener 55 such as a slide fastener which in the present instance is shown as comprising complementary slide fastener tapes 15 and 16 one of which is connected to the free edge of each of the sections 12 and 13, for example, by lines of stitches 17, and has at its edge a plurality of fastener elements 18 of known type that are adapted to engage and disengage similar elements on the other tape upon movement of a slider 19 of known type longitudinally of the rows of fastener elements.

The sections 12 and 13 of the auxiliary abdominal support are non-elastic or substantially non-stretchable in all directions but are preferably shaped and stitched to the front sections of the garment along the lines 14 so that when the main portion of the garment is stretched circumferentially, with the slide fastener released, the disconnected edges of the sections 12 and 13 will be pulled apart, especially when the garment is pulled onto the body as shown in FIGURE 2, and the proportions and

shape of the sections of the abdominal support are such that upon pulling of the slider upwardly on the garment the slide fastener is gradually closed and the auxiliary abdominal support sections are drawn toward each other circumferentially of the garment and body so as to thereby apply circumferential tension to the garment in such a way as to flatten and support the abdominal wall. It will be noted that when the slide fastener is closed as shown in FIGURE 1, the portion of the front panel of the garment that is overlaid by the abdominal support sections 12 and 13 while remaining elastic and taut on the body, is substantially non-stretchable due to the non-stretchability of the sections 12 and 13 so as to provide a firm support for the abdominal wall, while at the same time permitting free stretching of the other portions of the garment.

It is, of course, important that the auxiliary abdominal support portions be of such shape and size that when the garment is in its normal non-stretched condition, the free edge portions of the abdominal support sections are in close proximity to each other and unconnected, for example, as shown in FIGURE 3, while when the upper portion particularly of the garment is stretched circumferentially, said edge portions of the abdominal support sections are pulled apart to provide a V-shaped gap between them that gradually decreases in width or tapers from the upper edge of the garment toward the intermediate point in the length of the garment at which the sections are permanently and fixedly connected together either integrally or by some other means and are also directly connected to the front panel as by stitching.

It will be noted that a binding and finishing strip 20 is stitched to the upper edge portion of the garment and a similar strip 21 is stitched to the lower edge of the garment, but, of course, these structural details form no part of the invention.

While the invention has been shown as embodied in certain specific structural details, it should be understood that the details of construction of the invention may be modified and changed and the invention may be embodied in other circumferentially stretchable articles or garments, all within the spirit and scope of the invention.

I claim:

1. A body-encircling garment including a circumferentially continuous expandable and contractible main portion having upper and lower ends and a front zone that is expandable and contractible both longitudinally and circumferentially of the main portion, and an auxiliary abdominal support comprising two non-stretchable sections in partially overlying relation to said front zone, each connected continuously along one edge to said main portion between said upper and lower ends and having an opposite edge connected to said main portion from the upper end to a point between said upper and lower ends and otherwise free of said main portion and free from the corresponding edge of the other section, the second-

5 mentioned edges of said sections being normally pulled away from each other from said point to the upper end of the main portion upon expansion of the main portion, and a fastener means to pull and connect said second-mentioned edges together and thereby limit stretching of said main portion between the points of connection thereof of said sections of the auxiliary abdominal support while said second-mentioned edges are connected and at the same time exert a flattening action on the abdominal wall of the wearer of the girdle, said fastener means comprising a row of fastener elements on each of said second-mentioned edges for connection to and disconnection from fastener elements on the second-mentioned edge of the other section, and a slider coacting with said rows of fastener elements for connecting and disconnecting said fastener elements upon movement of the slider in opposite directions, respectively, longitudinally of said rows of said fastener elements.

2. A body-encircling garment as defined in claim 1 wherein said main portion comprises in addition to said front zone a rear panel that includes a central section formed of material that is elastic longitudinally of the garment from the upper end to the bottom end but is non-elastic circumferentially of the garment and two flank sections each of which is elastic both longitudinally and circumferentially of the garment and each has one edge stitched to one edge of the central section, said main portion also includes side panels that are non-elastic circumferentially of the garment but elastic longitudinally of the garment and each of which has one edge stitched to one edge of one of said flank sections, said front zone is a panel that comprises two sections elastic both longitudinally and circumferentially of the garment and each of which has one edge secured to one edge of the other from the upper end to the lower end of the main portion and its other edge secured to one edge of one of the side panels, and the first-mentioned edge of each section of the auxiliary abdominal support is stitched to one of the sections of the front panel, and the second-mentioned edges of the sections of the auxiliary abdominal support are connected together and to the front panel of the main portion between said fastener and the lower end of the main portion.
